EMIL L. MUELLER, OF RUTHERFORD, NEW JERSEY, ASSIGNOR OF ONE-HALF TO DAVID A. McINTYRE, OF NEWARK, NEW JERSEY

NUMBERING MACHINE

Application filed April 21, 1925. Serial No. 24,723.

This invention relates to a numbering machine, and particularly to a machine which is adapted for the printing of page numbers and the like for books and pamphlets.

5 An object of the invention is to provide a simple form of numbering machine by means of which the sheets of paper which are to form the pages of the book or pamphlet may be printed with correct numbers thereon either directly as they come from the main printing press or subsequently as may be desired.

In the making up of books it is customary to form the same of a plurality of separate sections each section consisting of two or more 15 separate sheets of paper folded midway so that each sheet provides two leaves and four pages and so that in each section these sheets will be connected together to form a section or 20 signature, of suitable thickness for handling and binding. In order to properly number the pages so that they will read consecutively through the several sections of the book it is apparent that numbers placed on the succeeding sheets as they issue from the main 25 printing press, or otherwise, will not be in numerical sequence, and it is therefore an object of the present invention to provide a numbering machine which will be readily 30 adapted to the printing of correct numbers in appropriate sequence so that when the sections, or signatures, are made up and bound into a book the numbers will appear in proper numerical sequence in the completed book.

35 In certain forms of books, such as in record books of different types, it is desirable that each two adjacent pages throughout the book be numbered with identical numbers so that the two pages appearing for inspection whenever the book is laid open will have the same number, and it is therefore a further object of the present invention to provide means for so numbering the sheets that when they are bound into sections, or signatures, 40 and the sections, or signatures, are placed side by side in the book the pages appearing for inspection as indicated will bear like numbers.

Other objects and aims of the invention, 45 more or less specific than those referred to

above, will be in part obvious and in part pointed out in the course of the following description of the elements, combinations, arrangements of parts and applications of principles constituting the invention, and the scope of protection contemplated will be indicated in the appended claims.

In the accompanying drawings which are to be taken as a part of this specification, and in which I have shown merely a preferred form of embodiment of the invention:

Fig. 1 is a diagrammatical side elevational view of a portion of a numbering machine embodying this invention.

Fig. 2 is a top plan view, partly in section, of the structure appearing in Fig. 1.

Fig. 3 is a view illustrating two simple book sections such as may be numbered by this machine, and

Fig. 4 is a diagrammatic view, similar to that seen in Fig. 1, but on a smaller scale, and illustrating an arrangement whereby the four page numbers usually required upon each sheet of paper in a book may be applied by the use of only two platen wheels whereas in the arrangement suggested by Fig. 1 four separate platen wheels are required.

Referring to the drawings for describing in detail the structure illustrated therein the reference character L indicates a type-wheel 80 about the periphery of which is a series of spaced projections as 1, 2 and 3 the outer peripheral faces of which are each cut or otherwise formed as printing type each projection being shaped to provide a different figure and there being as many projections as there are separate sheets of paper to be numbered for comprising the book in course of being printed.

85 Adjacent to the type-wheel is a platen wheel G carrying a single platen member H on the periphery thereof which is adapted to press an interposed sheet as 4 against one of the type-projections on the type-wheel.

90 Any suitable means may be employed for holding the sheet 4 and causing it to be carried around with the wheel G, there being indicated for this purpose a suitable gripper 5 arranged to engage the forward edge of the

100

sheet as the sheet comes off of a delivery table 6 and to clamp said edge of the paper against a part 7 of the platen wheel in a well understood manner.

5 The table 6 may be understood to be a part of the main printing press by means of which the sheet has been previously printed, or otherwise treated, so that it contains all of the reading matter or otherwise preparatory to binding.

10 The platen member H is preferably adjustable circumferentially of the wheel G and for this purpose the drawing indicates said member as being formed upon a carrying plate 8 which laps over the side of the wheel G and which carries retaining devices 9 extending into an undercut groove 10 formed circumferentially of the wheel G. By loosening the devices 9 the platen member may be 15 slid around the wheel G, the devices 9 meanwhile sliding in the groove 10, to any position desired and may be held in such position by tightening the devices 9. By this means the platen member may be caused to stand 20 nearer to or further from the clamp member 5 and therefore nearer to or further from the forward edge of the sheet 4 so that the figure from the type-wheel may be impressed at a 25 selected position upon the sheet.

30 It will be understood that in order to properly complete this adjustment the wheels L and G are at that time freely rotatable relative to each other so that any selected type-projection on the type-wheel may be made 35 to register with the platen member.

It is intended that after the sheet, as 4, has passed between the wheels L and G and has received therefrom the impression of one figure from the type-wheel it will then pass between two further wheels for receiving the impression of a second figure, then between two further wheels for receiving the impression of another figure, and finally between a fourth pair of wheels to receive the final 45 figure, thus impressing onto the sheet, and in proper locations thereon, the page numbers of the four pages which the sheet is to comprise when fixed in place in the book.

In the drawing Fig. 1 there is shown in association with the wheels L and G a portion as 11 of the next pair of wheels for operating upon the sheet after the sheet has passed between the wheels L and G. Adjacent to the under side of the wheel G is a table 12 upon which the sheet 4 will be deposited after leaving the wheel G. Any suitable means, as for instance the push device 13, may be employed in association with the table 12 to slide the sheet 4 off of said table and onto the wheel 11 where it will be gripped and carried on its way.

The sheet will pass similarly through the four sets of wheels but since each set is of identical construction and operation only one set is herein shown and described in detail.

The wheels L and G are fixed to suitable carrying shafts 14 and 15 respectively. These shafts are mounted in appropriate bearings 16 and 17 formed in a frame piece 18. Upon the shaft 14 is mounted a gear 19 which is 70 freely rotatable upon said shaft and which stands in constant mesh with a gear 20 fixed upon the shaft 15.

Upon the shaft 14 is a second gear 21 which is fixed to said shaft and which stands in constant mesh with the teeth of a drive pinion 22. The pinion 22 is mounted upon a bearing shaft 23 and is connected to be driven by any appropriate means as for instance a drive gear 24.

75 Mounted upon the shaft 14 is a third gear 25 also standing in constant mesh with the same teeth of the pinion 22 as the gear 21. The gear 25 however, although of the same pitch diameter as the gear 21 has one tooth less than said gear 21 and on this account will rotate at a slightly faster speed than the gear 21, a complete rotation of the gear 21 being in fact accompanied by a complete rotation of the gear 25 plus the distance of one 80 tooth of the gear 25.

85 The gear 25 is connected with the gear 19 by a suitable clutch device, as for instance the pin 26 carried by the gear 25 and engaging within a socket 27 provided in the gear 19, so that said gear 19, and consequently the gear 20, both of which are of the same pitch diameter, will rotate with the gear 25, as will 90 also the wheel H.

95 The gear 21, being fixed to the shaft 14, will cause the wheel L to move with it and consequently at a correspondingly slower speed than the wheel G.

100 There are as many type-projections on the wheel L as there are teeth in the gear 25. The type-projections are thus spaced apart a distance corresponding to the distance between the teeth of the gear 25 and it will be apparent therefore that each time the platen member H comes around into contact with 105 the type-wheel it will engage a succeeding type-projection of said type-wheel.

110 Referring to Fig. 1 the platen member is shown as in engagement with the type-projection carrying the Figure 1. At the first 115 rotation of the two wheels the platen member will come into engagement with the type-projection carrying the Figure 2. At the next rotation it will come into engagement with the type-projection carrying the Figure 120 5. At the next rotation it will come into engagement with the type-projection carrying the Figure 6, and so on.

125 When the full cycle of the type-projections on the wheel L has been completed a new cycle will begin without interruption, and here it will be noted that the total number of type-projections on the wheel L is determined by the total number of pages which are to appear in the book being printed. The wheel 130

L would carry projections for one-fourth of the total number of pages and the corresponding wheel of the other three sets of wheels would each carry another fourth.

5 The figures appearing upon the type-projections of the several wheels will of course be given a sequence according to requirement. Assuming, for example, that the machine is being utilized for printing the four sheets 10 of paper comprising the two book sections illustrated in Fig. 3, and noting that in these book sections the adjacent pages bear like numbers, the first pair of wheels, as L and G, will print onto the first sheet the page number, or figure, 1, onto the second sheet the page number 2, onto the third sheet the page number 5, and onto the fourth sheet the page number 6. The second pair of wheels would print on the first sheet the page number 4, onto the second sheet the page number 3, onto the third sheet the page number 8, and onto the fourth sheet the page number 7. The third pair of wheels would print onto the first sheet the page number 3, onto the second sheet the page number 2, onto the third sheet the page number 7, and onto the fourth sheet the page number 6. The final pair of wheels would print nothing on the first sheet, onto the second sheet it 30 would print the page number 1, onto the third sheet the page number 4, and onto the fourth sheet the page number 5.

As these sheets issue one after the other from the machine and are folded into sections 35 as indicated in Fig. 3 the page numbers would read in proper sequence as illustrated.

The gear wheels 21, 22 and 25 and the type-wheel L constitute a unit, that is to say they are cooperative with each other to properly number the pages of a book having a given 40 number of pages. In order to number the pages of a book having a different number of pages the parts comprising this unit would be removed and substituted by another unit 45 the parts of which would be cooperative in the same manner but there being a different number of type-projections on the type-wheel and a correspondingly different number of teeth in the gears. In the instance illustrated 50 the gears 21 and 25 may be readily detached by removal of the retaining pin 28. The pinion 22 may be removed by removal of its retaining pin 29, and the type-wheel may be removed by removal of its retaining pin 30. Any suitable means, as for instance the ink 55 roll 31 may be provided for inking the printing surface of the type-projections on the type-wheel.

While this invention is applicable to the 60 printing of page numbers in various types of books it is nevertheless peculiarly adapted to the numbering of pages in books where the printed matter on all of the pages is alike, as for instance in certain classes of 65 receipt and record books such as are used

by collecting agents for insurance companies and other large organizations, since in these instances the page numbers may be readily applied by this invention upon the succeeding sheets as they issue from the main printing press in the manner above described and thus the book sections, and finally the books, may be printed one after the other ready for immediate binding. Any desired number of books may be thus printed and bound wholly 70 without reference to how many books are required or how many have been printed, or otherwise, as has been an aggravating requirement in the numbering of pages of this 75 class of books heretofore.

As has been herein-above suggested the modification Fig. 4 offers an arrangement whereby the use of two of the platen wheels required for printing page numbers at the four different localities as described with respect to Fig. 1 may be omitted. Instead of employing four separate units each containing a platen wheel and a printing wheel the illustration Fig. 4 proposes only two 80 separate units each comprising a platen wheel as G and two printing wheels 32 and 33. As the sheet of paper as 4 passes about the first platen wheel it receives the impression of two page numbers at proper locations thereon from the two printing wheels associated with that platen wheel, these impressions being of course both on the same surface of the sheet. Upon leaving the first platen wheel the sheet is caught by the gripper 5 and carried around the second platen wheel. In passing around the second platen wheel it receives the impression of two page numbers at proper locations on its opposite surface by means of the pair of printing wheels 32 and 33 associated with the second platen wheel, after 90 which it is deposited onto the delivery table 34, from whence it is removed when a sufficient number of sheets have been deposited thereon to constitute a signature.

Suitable means will of course be provided to prevent the different platen members H on each platen wheel from producing impressions from more than one printing wheel, as for instance the platen members may be placed slightly out of alignment with respect to each other, as will likewise the printing wheels, so that no printing pressure will be produced excepting against the type of the proper printing wheel.

It will be understood of course that the drive mechanism for the wheels suggested by this modification will be substantially the same as already set forth with regard to the disclosure Figs. 1 and 2.

As many changes could be made in this construction without departing from the scope of the invention as defined in the following claims, it is intended that all matter contained in the above description or shown 125

in the accompanying drawings, shall be interpreted as illustrative only and not in a limiting sense.

Having thus described my invention, what I claim as new and desire to secure by Letters Patent is:—

1. A numbering machine comprising a pair of wheels having juxtaposed peripheral portions, means to rotate said wheels and to cause sheets to pass between them one at each complete revolution of said wheels, one of said wheels having a series of printing characters spaced apart thereon, the other wheel having a platen member for pressing the sheets against said printing characters, and means whereby the platen member will press succeeding sheets against different printing characters, a guide member carried by the second wheel to determine the position of the sheet upon the second wheel, and means whereby the platen member is adjustable with respect to the guide member for the purpose set forth.

2. A numbering machine comprising a pair of wheels having juxtaposed peripheral portions, means to rotate said wheels and to cause sheets to pass between them one at each complete revolution of said wheels, one of said wheels having a series of printing characters spaced apart thereon, the other wheel having a platen member for pressing the sheets against said printing characters, and means whereby the platen member will press succeeding sheets against different printing characters, said last mentioned means comprising a single drive gear, a second gear meshing with the teeth of said drive gear and being connected to in turn drive one of said wheels, and a third gear having a different number of teeth as compared with the second gear but meshing with the same teeth of said first gear and being connected to drive the second wheel.

3. A numbering machine comprising a printing wheel and a platen wheel said wheels having juxtaposed peripheral portions, means to rotate said wheels and to cause sheets to pass between them one at each complete revolution of said wheels, said printing wheels having a series of printing characters spaced apart circumferentially thereof, said platen wheel having a platen member at one point in its periphery for pressing the sheets against the printing characters of the printing wheel, and means whereby the platen member will press succeeding sheets against successive printing characters of the printing wheel, said last mentioned means comprising a drive gear, a second gear meshing with the teeth of the drive gear and being connected to in turn drive the platen wheel, the number of teeth on the second gear being the same as the number of printing characters on the wheel, and a third gear meshing with the same

teeth of the drive gear and being connected to drive the printing wheel but said third gear having one more tooth than said second gear.

4. A numbering machine comprising a printing wheel and a platen wheel said wheels having juxtaposed peripheral portions, means to rotate said wheels and to cause sheets to pass between them one at each complete revolution of said wheels, said printing wheel having a series of printing characters spaced apart circumferentially thereof, said platen wheel having a platen member at one point in its periphery for pressing the sheets against the printing characters of the printing wheel, and means whereby the platen member will press succeeding sheets against successive printing characters of the printing wheel, said last mentioned means comprising a drive gear, a second gear meshing with the teeth of the drive gear and being connected to in turn drive the platen wheel, the number of teeth on the second gear being the same as the number of printing characters on the printing wheel, and a third gear meshing with the same teeth of the drive gear and being connected to drive the printing wheel but said third gear having one more tooth than said second gear, together with means whereby said printing wheel and all of said mentioned gears are detachably connected with the platen wheel for the purpose set forth.

5. A numbering machine comprising a pair of platen wheels, two printing wheels for each platen wheel, means to rotate said wheels and to cause sheets to pass between one of said platen wheels and its printing wheels for receiving separate impressions on one surface of the sheet from said mentioned printing wheels and to cause said sheets to thereafter pass between the second platen wheel and the second two printing wheels to thereby receive further separate impressions from said last two printing wheels on the opposite surface of the sheet, and means whereby succeeding sheets will receive different impressions from all of said wheels.

6. A numbering machine comprising a printing wheel and a platen wheel said wheels having juxtaposed peripheral portions, means to rotate said wheels and to cause sheets to pass between them one at each complete revolution of said wheels, said printing wheels having a series of printing characters spaced apart circumferentially thereof, said platen wheel having a platen member at one point in its periphery for pressing the sheets against the printing characters of the printing wheel, and means whereby the platen member will press succeeding sheets against successive printing characters of the printing wheel, said last mentioned means comprising a drive gear, a second gear mesh-

ing with the teeth of the drive gear and being connected to in turn drive the platen wheel, and a third gear meshing with the same teeth of the drive gear and being connected to drive the printing wheel but said third gear having one more tooth than said second gear.

7. A numbering machine comprising a printing wheel and a platen wheel said wheels having juxtaposed peripheral portions, means to rotate said wheels and to cause sheets to pass between them one at each complete revolution of said wheels, said printing wheel having a series of printing characters spaced apart circumferentially thereof, said platen wheel having a platen member at one point in its periphery for pressing the sheets against the printing characters of the printing wheel, and means whereby the platen member will press succeeding sheets against successive printing characters of the printing wheel, said last mentioned means comprising a drive gear, a second gear meshing with the teeth of the drive gear and being connected to in turn drive the platen wheel, and a third gear meshing with the same teeth of the drive gear and being connected to drive the printing wheel but said third gear having one more tooth than said second gear, together with means whereby said printing wheel and all of said mentioned gears are detachably connected with the platen wheel for the purpose set forth.

8. A numbering machine comprising a printing wheel and a platen wheel said wheels having juxtaposed peripheral portions, means to rotate said wheels and to cause sheets to pass between them one at each complete revolution of said wheels, said printing wheel having a series of printing characters spaced apart circumferentially thereof, said platen wheel having a platen member at one point in its periphery for pressing the sheets against the printing characters of the printing wheel, and means whereby the platen member will press succeeding sheets against successive printing characters of the printing wheel, said last mentioned means comprising a drive gear, a second gear meshing with the teeth of the drive gear and being connected to in turn drive the platen wheel, and a third gear meshing with the same teeth of the drive gear and being connected to drive the printing wheel but said third gear having one more tooth than said second gear, together with means whereby said printing wheel and said second gear are detachably connected with the platen wheel for the purpose set forth.

9. A numbering machine comprising a pair of wheels having juxtaposed peripheral portions, means to rotate said wheels and to cause sheets to pass between them one at each complete revolution of said wheels, one of said wheels having a series of printing

characters spaced apart thereon, the other wheel having a platen member for pressing the sheets against said printing characters, and means whereby the platen member will press succeeding sheets against different printing characters, said last mentioned means comprising a single drive gear, a second gear meshing with the teeth of said drive gear and being connected to in turn drive one of said wheels, and a third gear having a different number of teeth as compared with the second gear but meshing with the same teeth of said first gear and being connected to drive the second wheel, together with means whereby one of said wheels and all of said gears are detachably connected with the other wheel for the purpose set forth.

10. A numbering machine comprising a pair of wheels having juxtaposed peripheral portions, means to rotate said wheels and to cause sheets to pass between them one at each complete revolution of said wheels, one of said wheels having a series of printing characters spaced apart thereon, the other wheel having a platen member for pressing the sheets against said printing characters, and means whereby the platen member will press succeeding sheets against different printing characters, said last mentioned means comprising a single drive gear, a second gear meshing with the teeth of said drive gear and being connected to in turn drive one of said wheels, and a third gear having a different number of teeth as compared with the second gear but meshing with the same teeth of said first gear and being connected to drive the second wheel, together with means whereby one of said wheels and the gear for the other wheel are detachably connected with said other wheel for the purpose set forth.

11. A numbering machine comprising a printing wheel and a platen wheel said wheels having juxtaposed peripheral portions, means to rotate said wheels and to cause sheets to pass between them one at each complete revolution of said wheels, said printing wheels having a series of printing characters spaced apart circumferentially thereof, said platen wheel having a platen member at one point in its periphery for pressing the sheets against the printing characters of the printing wheel, and means whereby the platen member will press succeeding sheets against successive printing characters of the printing wheel, said last mentioned means comprising a drive gear, a second gear meshing with the teeth of the drive gear, a shaft upon which said second gear is freely rotatable, a third gear fixed to said platen wheel to rotate the platen wheel, a fourth gear meshing with the third gear being mounted to rotate loosely upon said mentioned shaft, means by which the second and fourth mentioned gears are separately con-

- 5 nected together, the printing wheel being connected with said mentioned shaft, and a fifth gear connected to said mentioned shaft to rotate said shaft and printing wheel and being in mesh with the same teeth of the drive gear as said second mentioned gear, but said fifth gear having a different number of teeth as compared with the number of teeth of the second mentioned gear.
- 10 12. In a page numbering machine, conveying means by which to convey a succession of sheets sufficient to constitute a signature, printing means associated with said conveying means operable to print a separate page numeral upon each of at least four page forming portions of each of the successive passing sheets, and means operable upon the printing means to differ the page numerals printed upon succeeding sheets and to thereby insure a predetermined consecutive relationship of succeeding page numerals in the signature.
- 15 13. In a page numbering machine, conveying means by which to convey a succession of sheets sufficient to constitute a signature, printing means associated with said conveying means operable to print page numerals on spaced portions of one face of each of the passing sheets, other printing means associated with the conveying means operable to print page numerals on spaced portions of the opposite face of each of the passing sheets, means to receive the printed sheets one after the other preparatory to folding 30 into signature form, and means to insure that the mentioned numerals as they occur in the signature shall be in general numerical sequence with similar page numerals on each two opposing pages said means including 35 mechanism operable upon the printing means to insure the printing of non-consecutive numerals by the printing means and to differ the numerals printed by the printing means upon succeeding sheets.
- 40 45. In testimony whereof I affix my signature.
EMIL L. MUELLER.
